COMPRESSOR VALVE STRUCTURE

Clifford S. Cody, East Springfield, Mass., assignor to Westinghouse Electric & Manufacturing Company, East Pittsburgh, Pa., a corporation of Pennsylvania

Application July 14, 1936, Serial No. 90,453

10 Claims. (Cl. 230—228)

My invention relates to a valve structure for compressors or the like, and it has for an object to provide an improved valve structure.

A further object is to provide suction and discharge valves of adequate flow areas.

Another object is to reduce the volumetric clearance of the compressor, that is, the space between the piston and the discharge valve at the end of the compression stroke.

10 A further object is to provide increased valve opening movement of the suction valves without increasing the stress.

These and other objects are effected by my invention as will be apparent from the following 15 description and claims taken in connection with the accompanying drawing, forming a part of this application, in which:

Fig. 1 is a plan view of the valve structure, a part of the compressor, with the cylinder head removed, as seen along the line I—I of Fig. 3;

Fig. 2 is a section, taken on the line II—II of Fig. 1, showing a discharge valve;

Fig. 3 is a section, taken on the line III—III of Fig. 1, showing the valve structure and a portion of the compressor;

Fig. 4 is a plan view of the sheet member containing the movable element of the suction valve;

Fig. 5 is a plan view of the movable elements of the two discharge valves; and,

30 Fig. 6 is a plan view as seen along the line VI—VI of Fig. 3.

Referring to the drawing in detail, I show, in Figs. 1 and 3, a portion of a refrigerant compressor in which my novel valve structure is embodied. The compressor includes a cylinder member 10 having a cylinder 11 provided therein and a piston 12 operating in the cylinder 11. The cylinder member is formed with a portion 13 projecting laterally from the cylinder at the upper end thereof. A sheet metal member 14, shown in Fig. 4, is placed against the top of the cylinder member 10, a valve plate 15 is placed on top of the sheet member 14, and a cylinder head 16 is positioned on top of the valve plate 15 with a gasket 15' preferably inserted therebetween. The head 16 is bolted to the cylinder member 10, the positions of the bolts being indicated in Fig. 1 by the bolt-holes 17, and the cylinder member 10. The sheet member 14 and the valve plate 15 are thus clamped between the head and the cylinder member.

The valve plate 15 is formed with a suction port 18 communicating with the cylinder and disposed adjacent one side thereof. The sheet member 14 which is preferably made of a strong

and resilient metal, such as Swedish steel, is cut as shown in Fig. 4 to provide a tongue or flap 19. The latter has an enlarged free end 20, which is circular and of sufficient diameter to close the port 18 in the valve plate 15. The port 18 and free end 20 of the flap 19 are so positioned with respect to the cylinder 11 that the tip of the flap projects slightly beyond the cylinder 11, as shown in Figs. 3 and 6. A recess 21 is formed in the cylinder member to accommodate said projecting tip, and the lower side of this recess constitutes a stop for limiting the downward movement of the free end of the flap 19.

The flap 19 is of substantially greater length than the diameter of the cylinder 11, and at the 15 end at which it is connected to the sheet member 14, it projects considerably beyond the cylinder as shown in Figs. 3 and 6. The upper surface of the cylinder member 10 is relieved, as indicated at 22 in Figs. 3 and 6 to permit this projecting 20 portion of the flap 19 to move away from the valve plate 15. The flap 19 is thus free to flex along a long radius of curvature when the same is moved to open the suction port 18. The free end 20 of the flap 19 may thus move a substantial 25 distance away from the valve plate 15 to provide adequate opening for flow of low pressure vapor during the suction stroke, without sharp bending of the flap 19. Adequate flow area through the suction port is thus obtained while at the same 30 time providing long life of the flap 19.

The relieved surface 22 may be of any suitable form. It may be of circular arc form conforming to the circular arc along which the flap 19 is bent when the tip thereof touches the lower side of the recess 21, or it may be formed along a straight line so that the edge at the cylinder 11 just touches or nearly touches the flap 19 when the latter is so bent. The relieved portion preferably extends to the right nearly to the junction between the flap 19 and the remainder of the sheet metal member 14.

To provide for the discharge valves, the valve plate 15 is formed with a depression or recess 23 in its upper surface, the contour of the recess 45 being shown in Fig. 1. The recess is formed with an inclined surface 24 as will be seen from Figs. 2 and 3. At the lowermost portion of the inclined surface, where the recess thus forms a portion of valve plate of minimum thickness, the 50 valve plate is formed with two discharge ports 25 located on opposite sides of the flap 19. Two discharge valve elements 26 comprising strips of flexible thin sheet metal such as Swedish steel, are disposed along the inclined surfaces, extend- 55

ing in an inclined direction, that is, in the direction of incline of the surface 24. The lower or free ends of the valve strips shown at the left-hand end of the drawing, are adapted to close the upper ends of the ports 25, the inclined surface being formed with lands or raised surfaces around the edge of the ports 25 so that the valve elements 26 actually contact only along the narrow surfaces of these lands.

10 The opposite ends of the valve elements 26 are fixed against the upper end of the inclined surface, at a point adjacent the top surface of the valve plate. They are clamped between the inclined surfaces of the valve plate and a stop member 27, the latter being secured to the valve plate by means of a screw 28 and a nut 29. The valve elements 26 and the stop member 27 are positioned in proper relation to the valve plate 15 by means of pins 30, which are inserted in registering openings 31 in the stop member, the valve elements 26, and the valve plate 15. The upper ends of the openings 31 in the stop member 27 are closed by the nut 29. The lower side 32 of the stop member 27 constitutes a stop for the discharge valve elements 26 in valve opening position. Grooves 32' are formed in said lower side 32 to minimize the suction effect of the stop member 27 tending to hold the valve element 26 in open position. Said lower side 32 of the stop member 27 is curved along a circular arc of sufficiently long radius so that the discharge elements 26 may flex along said arc, thereby avoiding any sharp bending of these valves. As will be noted from Fig. 4, the sheet member 14 has openings 33 registering with the ports 25 to provide unrestricted communication between the cylinder and the discharge ports 25. The valve plate 15 is formed with a rib 34 between the discharge ports 25 to provide increased strength for the valve plate in the region of the portion of reduced thickness.

40 By providing the recess 23 to depress the discharge valves, the volume of space comprising the discharge ports 25 is greatly reduced. In this way, I am able to greatly reduce the volumetric clearance of the compressor, that is, the space between the piston and the discharge valves. This space contains compressed gas at the end of the discharge stroke, which compressed gas re-expands and fills a portion of the volume of the cylinder upon the suction stroke of the piston. The volume of the re-expanded gas decreases, by the same amount, the quantity of low pressure gas that is drawn into the cylinder to be compressed and thus reduces the volumetric efficiency of the compressor. Thus, by reducing the volume of the discharge ports 25 to a minimum, the amount of such re-expansion is minimized and the volumetric efficiency of the compressor is increased.

60 By disposing the ports 25 on opposite sides of the flap 19, I avoid conflict with the flap 19 and make advantageous use of that portion of the end of the cylinder which is not required for the suction valve. It will thus be seen that I have provided an advantageous arrangement of suction and discharge valves, whereby adequate flow area of both suction valve and discharge valve is provided.

70 The cylinder head 16 is provided with a suction passage 35, one end of which is adapted to be connected to a suction conduit 36 and the other end of which registers with the suction port 18. It is also formed with a recessed chamber 37 registering with the recess or depression

23 in the valve plate 15 and accommodating the nut 29 and a portion of the stop member 27. A passage 38 leads from the chamber 37 and connects with a discharge conduit 39. The integral portion of the head between the passage 35 and the chamber 37 forms a partition 41.

75 While the cylinder head and the valve plate have been shown as separate parts, it will be apparent that they may be made in one piece without departing from the invention.

10 While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

15 What I claim is:

20 1. In a compressor or the like, the combination of a cylinder member having a cylinder formed therein, an end member secured to said cylinder member for closing one end of said cylinder and having a section port formed there-in adjacent one side of the cylinder; and a resilient valve reed or strip disposed between said members, said valve strip having a free end movable into the cylinder and cooperating with said port to form a suction valve for the compressor and the other end being fixed between said members at a point spaced from the cylinder and on the side of the latter remote from said port so that the valve strip extends across the cylinder, said cylinder member being recessed to permit the portion of the valve strip between the cylinder and the fixed end to flex with the free end upon valve opening, whereby the valve strip may flex along a long radius of curvature upon valve opening.

40 2. In a compressor or the like, the combination of a cylinder member having a cylinder formed therein, a valve plate disposed against the cylinder member at the end of said cylinder, a resilient valve strip extending across the end of the cylinder adjacent the valve plate and extending beyond the cylinder at each end, said valve strip being fixed adjacent one end and the other end being free, the free end being movable into the cylinder, said cylinder member having a recess adjacent said fixed end to permit the valve strip to flex away from said valve plate and having a recess adjacent the free end to limit movement thereof away from said valve plate, the valve plate having a port cooperating with the free end of said valve strip to form a suction valve for the compressor.

45 3. In a valve structure for a compressor or the like, the combination of a valve plate, said valve plate having substantially parallel opposite surfaces, a depression formed in one of said surfaces to provide a portion of reduced thickness of valve plate, and a port extending through said portion of reduced thickness; and a resilient valve reed or strip having a free end adapted to cooperate with said port to form a discharge valve for the compressor, the other end of the valve strip being fixed to said valve plate at a point spaced from said port and adjacent said one surface; said valve strip extending in an inclined direction from said free end to said fixed end.

50 4. In a valve structure for a compressor or the like, the combination of a valve plate, said valve plate having substantially parallel opposite surfaces, a depression formed in one of said surfaces

- to provide a portion of reduced thickness of valve plate, said depression having a surface inclined from the bottom of the depression to a point adjacent said one surface, and a port extending 5 through a portion of the valve plate of minimum thickness adjacent the lower end of the inclined surface; and a resilient valve reed or strip disposed along said inclined surface, said valve strip being secured to the valve plate adjacent the upper 10 most portion of the inclined surface, and the opposite end being free to cooperate with said port to form a discharge valve for the compressor.
5. In a compressor or the like, the combination of a cylinder member having a cylinder formed 15 therein, a valve plate located to close one end of said cylinder and having formed therein a discharge port communicating with said cylinder, said valve plate being recessed on the side remote from the cylinder in the region surrounding said 20 discharge port, and a resilient valve strip fixed at one end and having a free end extending into said recess and cooperating with said discharge port to form a discharge valve for the compressor.
6. In a compressor or the like, the combination 25 of a cylinder member having a cylinder formed therein; a valve plate closing one end of said cylinder and having formed therein a discharge port communicating with said cylinder, said valve plate being recessed on the side remote from the 30 cylinder in the region surrounding said discharge port to provide a valve plate portion of reduced thickness; and a resilient valve reed or strip having a free end extending into said recess and cooperating with said discharge port to form a discharge 35 valve, said valve strip extending in an inclined direction from said discharge port to a portion of the valve plate of greater thickness and being fixed to said portion of greater thickness.
7. In a compressor or the like, the combination 40 of a member having a cylinder therein, a valve plate disposed against said cylinder member at one end of said cylinder, a resilient suction valve strip disposed between said plate and said cylinder member and extending across the cylinder, one 45 end of the valve strip being fixed and the other end being free, said valve plate having a suction port cooperating with the free end of said valve strip to provide a suction valve and having two discharge ports disposed on opposite sides of the valve strip, and discharge valve elements disposed 50 on the opposite side of the valve plate and cooperating with said discharge ports to provide discharge valves for the compressor.
8. In a compressor or the like, the combination of a member having a cylinder therein, a valve plate disposed against said cylinder member at one end of said cylinder, a resilient suction valve strip disposed between said plate and said cylinder member and extending across the cylinder, one end of the valve strip being fixed beyond the cylinder and the other end being free, said valve plate having a suction port cooperating with the free end of said valve strip to provide a suction valve and having two discharge ports disposed on opposite sides of the valve strip, and discharge valve elements disposed on the opposite side of the valve plate and cooperating with said discharge ports to provide discharge valves for the compressor. 5
9. In a compressor or the like, the combination of a member having a cylinder therein, a valve plate disposed against said cylinder member at one end of said cylinder, a resilient suction valve 20 strip disposed between said plate and said cylinder member and extending across the cylinder, one end of the valve strip being fixed and the other end being free, said valve plate having a suction port cooperating with the free end of said valve strip to provide a suction valve and having two discharge ports disposed on opposite sides of the valve strip, and discharge valve elements disposed on the opposite side of the valve plate and cooperating with said discharge ports to provide discharge valves for the compressor. 15
10. In a compressor or the like, the combination of a cylinder member having a cylinder formed 25 therein, an end member secured to said cylinder member for closing one end of said cylinder and having a suction port formed therein, and a resilient valve reed or strip disposed between said members, said valve strip having one 30 portion movable into the cylinder and cooperating with said port to form a suction valve for the compressor and having one end retained between said members beyond the cylinder, said cylinder member being recessed to permit a portion of the 35 valve strip between the cylinder and said one end to flex with said one portion upon valve opening, whereby the valve strip may flex along a long line of curvature upon valve opening. 40
